PUNCH-RETAINING ASSEMBLY

Otto Mueller, Dearborn, Mich.

Application December 7, 1949, Serial No. 131,571

15 Claims. (Cl. 279—91)

1 This invention relates broadly to new and useful improvements in punch presses and more particularly to an improved assembly for mounting punches in the punch-carrying plates of such presses.

Punch presses of the type here under consideration are conventionally equipped with a plate which carries one or more punches. The punches extend through a stripper plate disposed below and spaced from the punch-carrying plate, and the punches are advanced against the work by a force-applying plate behind the punch-carrying plate. All of the above parts are assembled together with various supporting means and operating mechanisms.

It is essential that the punches be fastened solidly to the punch-carrying plate. Also, it is essential that the punches be readily removable from the plate as the punches are frequently broken in use. Broken punches must be replaced and the machine is rendered inoperative during the interval required for replacement.

Heretofore it has been necessary to remove a relatively large number of parts from the press in order to replace a broken punch, due primarily to the manner in which the punches are assembled on the punch-carrying plate. As a result it is necessary to shut the machine down for a considerable length of time each time a punch is broken. Such shutdowns are expensive, since neither the machine nor its operator earns anything during this time and a separate maintenance crew usually must be called in to service the machine. This complicated way of mounting the punches in the punch-carrying plate has been considered necessary heretofore in order to hold the punches solidly in place and to provide sufficient bearing surface to position the punch with requisite accuracy.

An important object of the present invention is to provide novel means for fastening punches to the punch-carrying plate so as to permit a broken punch to be replaced in a relatively short time.

Another object of the invention is to provide a novel punch-retaining assembly for presses of the above-mentioned character that makes it possible to replace a broken punch without disassembling large, heavy parts of the machine as heretofore required.

Still another object of the invention is to provide a punch-retaining assembly that holds the punch attached solidly to the punch-carrying plate.

Yet another object of the invention is to pro-

2 vide a punch-retaining assembly which holds the punch centered precisely on the punch-carrying plate.

A further object of the invention is to provide a punch-retaining assembly having novel means for holding the punch properly positioned angularly about its axis.

Other objects and advantages of the invention will be apparent during the course of the following description.

In the drawings forming a part of this specification and wherein like numerals are employed to designate like parts throughout the same:

Considered in certain of its broader aspects

55 the punch-retaining assembly embodying the

present invention comprises a retainer sleeve which is carried by the punch-carrying plate and is formed with a downwardly directed opening. This opening has an internally threaded portion and an accurately ground cylindrical portion below the internal threads. Also, a socket is provided in the opening behind the internal threads, which socket has an accurately ground, cylindrical surface. The punch is insertable upwardly into the opening of the sleeve and the inner end of the punch has an accurately ground, cylindrical surface which fits snugly in the socket. Also, the punch is provided with a radial, downwardly directed shoulder which is disposed below the socket and behind the internal threads of the retainer sleeve. A lock bushing fitting snugly around the punch is threaded into the retainer sleeve, and the inner end of the bushing seats against the radial shoulder of the punch to hold the latter solidly in the sleeve. The bushing must be removed from the sleeve whenever it is necessary to replace a punch, and to this end the bushing is formed with wrench-engaging portion which projects from the sleeve. Also, the bushing is formed immediately behind the wrench-engaging portion with an accurately ground, cylindrical surface which enters and snugly fits the ground, cylindrical surface of the sleeve opening.

When the bushing is tightened against the radial shoulder of the punch, it holds the latter solidly in the retainer sleeve; and when the parts are so assembled, the interfitting, ground surfaces co-operate to hold the punch centered precisely in the punch-carrying plate. In the case of noncircular punches, suitable means also are provided for holding the punch positioned non-rotatably in the punch-retainer assembly so that the punch properly enters the female die.

For a more detailed description of the invention, reference is first had to the drawings and particularly to Figs. 1 and 2 which show a preferred embodiment of the invention. In the drawings the numeral 10 designates the punch-carrying plate of a conventional punch press. This plate 10 is surmounted by a force-applying plate 12, and a stripper plate 14 is disposed therebelow and spaced therefrom. A punch 16 is carried by the plate 10 and, as clearly shown in the drawings, the punch projects downwardly into an opening 18 in the stripper plate 14. Only one punch 16 is here shown, but it will be readily understood that the plate 10 may carry any desired number of punches. The shape of the punches and the location thereof on the plate 10 of course varies according to the particular shape and location of the holes to be made in the work (not shown).

As suggested, the instant invention is concerned substantially entirely with means for fastening the punch 16 to the plate 10. According to the present invention, the punch-retaining assembly comprises a retainer sleeve 20 disposed in and snugly fitting an opening 22 in the punch-carrying plate 10. At the upper end thereof, the sleeve 20 is formed with a radially enlarged head 24 which fits in a countersink 26 provided at the upper end of opening 22. The head 24 seats downwardly against an annular shoulder 28 at the juncture of opening 22 and countersink 26 and is held solidly against the shoulder by the force-applying plate 12. If necessary or desirable, the sleeve 20 may be provided with an external annular groove 30 at the juncture thereof with the head 24 to assure proper seating

engagement between the head 24 and the shoulder 28.

The punch 16 here shown has an elongated, cylindrical shank formed with a reduced, cylindrical punching portion 34 at one end and a radially enlarged head 36 at the other end thereof. In so far as the present invention is concerned, it is significant to note that the head 36 is provided with an accurately ground, cylindrical, peripheral surface which snugly fits the accurately ground, cylindrical wall of a socket 38 provided at the inner end of sleeve 20. These accurately ground, cylindrical surfaces cooperate to center the punch precisely in the sleeve 20 and to hold the inner end of the punch 16 fixedly positioned. A cylindrical blank or spacer 40 is provided in the socket 38 behind the head 36 to have the ends of punches 16 of standard lengths disposed in different planes for punching holes in a workpiece having offset portions. The socket, sleeve, and bushing are lengthened to support the standard punches backed by the blank 40 of proper thickness, and in such arrangement like punches are employed in all the sleeves and bushings in the assembled punch plate.

In order to hold the punch 16 in the retainer sleeve 20, a locking bushing 42 is provided which fits snugly around the cylindrical shank portion of the punch and is threaded into the sleeve below the socket 38. At its inner end, the bushing 42 seats solidly against the head 36 to hold the parts assembled. In order to assure a proper seating engagement between the bushing 42 and the head 36, the punch 32 preferably is formed immediately below the head with a portion 44 of reduced diameter. The lower portion of bushing 42 extends downwardly from the sleeve 20 and the projecting portion 46 thereof preferably is fashioned to provide wrench-receiving faces to assist in screwing the bushing into or from the sleeve 20. Immediately behind the wrench-engaging portion 46 of the bushing 42 is an accurately ground, annular surface 48 which snugly fits an accurately ground, internal, annular surface 50 at the lower end of sleeve 20. Also, the shank portion 32 of the punch 16 and the internal surface of bushing 42 are accurately ground to hold the punch solidly and precisely centered.

Upon the removal of the pressure plate 14, the punch 16 can be easily removed from the plate 10 merely by unscrewing the bushing 42. The sleeve 20 is prevented from turning during tightening or loosening of the bushing in any suitable manner as by means of a pin 52 at the interface between the head 24 and the punch-carrying plate 10 (Fig. 2). As soon as the external threads of the bushing 42 disengage the internal threads of sleeve 20, the bushing will drop down to entirely release the punch 16 and the latter then can be easily removed from the sleeve 20.

Conversely, to insert a new punch in the sleeve 20 it is necessary merely to assemble the bushing 42 on the punch and insert the assembled parts upwardly into the sleeve. The bushing 42 can be easily and quickly threaded into the sleeve 20 and when tightened it holds the punch solidly in place. The accurately ground annular surfaces hereinabove specifically referred to co-operate to hold the punch precisely centered in the plate 10. Thus, after the removal of the pressure plate 14, only a few minutes is required to replace any punch on the plate 10, and it is not necessary to remove or disassemble any other parts of the press 75 proper in order to effect removal of a punch.

The form of the invention shown in Figs. 3 and 4 is primarily adapted and pre-eminently suited for use with punches which are made of expensive material such as tungsten carbide. It is not practical to make such punches in the form shown in Fig. 1, since in making the punch it must be trimmed down from the diameter of the head 36. In the case of hard materials such as tungsten carbide, this trimming operation would be exceedingly difficult and the material removed would be wasted. Accordingly, in such cases I propose to use the construction shown in Figs. 3 and 4.

Except for the punch, the second form of the invention now described is identical to the form shown in Figs. 1 and 2. The punch 54 here shown is uniform in diameter throughout its length except for the reduced punching end 56 and an annular groove 58 adjacent the inner end thereof. This construction requires the removal of only a small amount of material to make the reduced punching end 56 and groove 58. A ring 60 is shrunk into groove 58 and the latter is positioned on the punch 54 so that the ring provides an annular shoulder on the sleeve 20 corresponding to the under surface of head 36 in the first form of the invention. In Figs. 3 and 4 the inner end of punch 54 is piloted snugly in the socket 38, and the other parts of the assembly cooperate in the manner described to hold the punch properly centered in the punch plate 10.

The form of the invention shown in Figs. 5 and 6 is primarily adapted for punches having noncircular punching ends. A punch 62 of this type is shown in the drawings. Manifestly, these punches must be properly positioned angularly or rotatably in the punch-carrying plate 10 in order that the punching die will cooperate properly with the female die (not shown). Accordingly, the punch-retaining assembly shown in Figs. 5 and 6 is modified slightly from the form of the invention shown in Figs. 1 and 2 in order to assure proper angular positioning of the punch.

In the latter form of the invention a spacer blank 64 of modified construction is employed instead of the spacer blank 40 as shown in the first form of the invention. The undersurface of spacer blank 64 is formed with a diametrical tongue 66 which enters and snugly fits a correspondingly shaped groove 68 in the top surface of the punch head 36. Also, the spacer blank 64 is positioned angularly in the sleeve 20 by a pin 70 at the interface between the blank and the sleeve (Fig. 6). Thus, in the form of the invention the pin 70 accurately positions the spacer blank 64 angularly within the sleeve 20, and the spacer blank in turn determines the angular position of the punch 62 in the assembly. Except for the above, the form of the invention shown in Figs. 5 and 6 is identical to the form of the invention shown in Figs. 1 and 2 and it enjoys the same advantages insofar as accurate positioning of the punch and convenience in assembling and disassembling is concerned.

The form of the invention shown in Figs. 7 and 8 illustrates still another way of holding a punch in a predetermined angular position in the punch-carrying plate 10. Except for the punch, this form of the invention is identical to the form shown in Figs. 1 and 2. The punch 72 here shown is formed with an integral, upward extension 74 on the head portion 16 thereof. The extension 74 is noncircular in form; and, in the form of the invention shown, is essentially square (Fig. 8). Extension 74 enters and snugly fits a correspondingly shaped opening 78 in the inner

end of sleeve 20. Manifestly, the extension 74 and opening 78 co-operate to hold the punch 72 in a predetermined, angular position in the punch-carrying plate 10. This maintains the alignment of the rectangular end 79 of the punch with the rectangular recess in the female die (not shown).

In connection with the foregoing it will be readily apparent that the extension 74 may have any desired outline which is noncircular in form. In the case of certain odd-shaped dies it may be necessary that the extension enter the opening in only one position of the die. If this is necessary the extension can be suitably shaped so that it enters the opening in only one position. Manifestly a number of shapes will accomplish this object.

The form of the invention shown in Figs. 9 and 10 is primarily adapted for situations where a plurality of individual punches must be mounted so closely together that they cannot be fastened separately to the plate 10. Two punches 80 and 82 are here shown. In this form of the invention the punches are mounted in a punch carrier 84 which is identical to the external shape of the punch 16 in the form of the invention first described and is held in the retainer sleeve 20 by bushing 42 in the same manner as the punch 16. Also, the punches 80 and 82 are identical in shape to the punch 16 as shown in Figs. 1 and 2. In the drawings, the punches 80 and 82 extend through properly located vertical openings 86 and 88 and the heads of the punches fit in suitable countersinks 90 and 92 at the upper ends of the opening. The carrier 84 is located angularly or rotatably in the sleeve 20 by an eccentrically positioned pin 94 which extends upwardly therefrom and into a socket 96 in the force-applying plate 12. The punches 80 and 82 here shown are circular in form and thus need not be positioned angularly in the carrier 84; however, if noncircular punches are employed they manifestly can be positioned angularly in the carrier in any suitable manner as by either of the two means shown in Figs. 5 and 7.

In view of the foregoing, it will be readily apparent that all of the punches in the gang can be removed simultaneously by merely unscrewing the lock bushing 42 and permitting the punch carrier 84 to drop out of the sleeve 20. Any or all of the punches associated with the carrier can be removed or replaced. Similarly, all of the punches in the gang can be fastened simultaneously in the plate 10 merely by inserting the carrier 84 and tightening lock bushing 42 against the shoulder defined by the head portion of the carrier.

In this form of the invention the sides of the punches are accurately ground and the bores 90 and 92 are also ground to snugly receive the punches so that the latter are solidly supported and accurately positioned.

Referring to Figs. 11 to 16 inclusive, a still further form of the invention is illustrated, that wherein the punch-retaining assembly is so constructed that a single length of punch may be utilized to service a press employing a plurality of punches which normally would be of different lengths. The assemblies are so constructed that even when the punches of standard length are ground to shorter lengths, the assembly may be adjusted to have the shorter lengths of punches projected further outwardly to be in the same position the end occupied before grinding.

The retainer sleeve 101 is similar to the sleeve 20 in the structure illustrated in Fig. 1, with the

exception that it is of greater length having a longer internal ground surface 102 for contact with the ground surface 103 of the bushing 104. As illustrated in Fig. 13, the sleeve 101 is secured against rotation to the plate 10 by a pin 106. The sleeve 101 has an enlarged internal recess 107 in which a separate plug 108 is provided so as to extend the end 109 of the punch 111 outwardly from the face of the plate 10 a greater amount than would occur if the punch were mounted on the plate without the use of the plug 108. Between the recess 107 for receiving the plug 108 and the threaded portion 112 of the sleeve, a square opening 113 having rounded corners is broached or otherwise formed in the sleeve. The enlarged head 114 of the punch 111 is provided with four flat sides 115 connected by round corner portions which mate with the flat sides and rounded corners of the aperture 113 to prevent the punch 111 from rotating, which prevention is desirable when the end 109 of the punch is of a shape other than cylindrical. In view of the length of the aperture 113 and the ground surface 102, different lengths of plugs 108 may be provided between the head 114 of the punch and the plug 108, to thereby advance the end 109 outwardly from the face of the plate 10.

It is contemplated that a substantial amount of the end 109 may be ground away at least to the dotted line 117 and the bushing moved downwardly with the punch the same amount as the plug 108 is increased in thickness. The head 114 of the punch may be provided with a threaded aperture 118 so that the plug 108, having an aperture 119 therethrough, may be secured to the head by a screw extending through the aperture 119 and threaded into the aperture 118. Sufficient bearing surface will be provided at all times between the flat faces of the head 114 and those of the aperture 113 and between the bushing and the surface 102 of the sleeve 101 to maintain accurate alignment and position for the punch 111.

In Fig. 12 a similar assembly is illustrated, with the exception that the plug 108 is omitted so that the end of the punch 111 will be closer to the face of the plate 10 than the punch in the assembly illustrated in Fig. 11, which amount will be equal to the length of the plug 108.

In Figs. 15 and 16, a similar assembly is illustrated for a gang of punches. In this arrangement the punch carrier 121 has the head 122 provided with flat sides 115 which mate with the flat sides of the square aperture 113 having the rounded corner portions located in the sleeve. A plug 108 may be provided for initially locating the ends of the punches 111 from the plate 10, and after the ends of the punches have been ground the plug 108 may be increased in thickness the amount ground from the ends of the punches so that when they are again assembled on the plate 10, the ends of the punches will project the same distance from the face thereof.

In Fig. 16 the plug 108 is initially omitted so that the ends of the punches 111 will project a standard distance from the face of the plate 10, and as the punches are ground off, a shim or plug 108 may be inserted between the head 122 and the plate 10 of the press, as illustrated in Fig. 15, to have the ends of the punches disposed the same distance from the face of the plate. By employing the opening 113 which is square or of any other polygonal or noncylindrical shape, the mating faces on the heads of the punches will remain in contact with the faces of the aperture as the punches and bushings are moved down-

wardly due to the grinding and shortening of the punches. If a tongue like 66 were relied upon for positioning the punch in the assembly, such a tongue would become inoperable as the head of the punch is adjusted downwardly in the assembly. The flat engaging surfaces being longer than the amount of adjustment of the assembly, the complete adjustment thereof may be made and still have the punch or punch carriers retained against rotation within the sleeve.

Having thus described the invention, I claim:

1. A punch-retaining assembly for punch presses of the type having a punch-carrying plate comprising a retainer sleeve capable of being supported by said punch-carrying plate and formed with an opening therethrough which is of reduced diameter near the top end forming a socket which is accurately ground concentric to the opening, said opening having an internally threaded portion medially of the ends and an accurately ground cylindrical portion at the bottom end concentric with and of larger diameter than said threaded portion; a punch in said retainer sleeve having a head portion in said socket and a ground shank portion in the opening below said socket, said head portion having an accurately ground, cylindrical, peripheral surface snugly fitting and guided by the ground, cylindrical surface of the socket to hold the punch centered precisely in said sleeve; and a lock bushing fitting snugly but slidably on the shank portion of said punch and having an external thread threaded into the threaded portion of said opening, the inner end of said bushing seating against the head of said punch to hold the latter solidly in the sleeve, said bushing having a wrench-engaging portion projecting from the sleeve and an accurately ground, cylindrical surface between said wrench-receiving portion and the thread snugly fitting and guided by the ground, cylindrical surface at said other end of the opening in the retainer sleeve for accurately aligning the punch within the sleeve and bushing in any position of longitudinal adjustment of the punch therein.

2. A punch-retaining assembly for punch presses of the type having a punch-carrying plate comprising a retainer sleeve adapted to be carried by said punch-carrying plate and formed with a downwardly directed opening extending completely therethrough, a portion of said opening near the top end forming a socket, said opening having an internally threaded portion below said socket and an accurately ground, cylindrical portion below said internal threaded portion and said socket having an accurately ground, cylindrical surface; a punch in said retainer sleeve having a head portion in and projecting from said socket and provided with a ground, cylindrical, peripheral surface snugly fitting and guided by the ground, cylindrical surface of the socket to hold the punch centered precisely in said sleeve; and a lock bushing fitting snugly but slidably on said punch and threaded into said opening, the inner end of said bushing seating against the projecting head portion of said punch to hold the latter solidly in the sleeve, said bushing having a wrench-engaging portion projecting from the sleeve and an accurately ground, cylindrical surface behind said wrench-receiving portion snugly fitting and guided by the ground, cylindrical surface of said opening to co-operate with said first-mentioned ground surfaces in

holding the bushing and said punch centered precisely in the sleeve.

3. A punch-retaining assembly for punch presses of the type having a punch-carrying plate comprising a retainer sleeve adapted to be carried by said punch carrying plate and formed with a downwardly directed opening extending completely therethrough, a portion of said opening near the top end forming a socket, said opening having an internally threaded portion below said socket and an accurately ground, cylindrical portion below said internal threaded portion, and said socket having an accurately ground, cylindrical surface; means for holding said retainer sleeve against rotation relative to said punch-carrying plate; a punch in said retainer sleeve having a head portion in and projecting from said socket and provided with a ground, cylindrical, peripheral surface snugly fitting and guided by the ground, cylindrical surface of the socket to hold the punch centered precisely in said sleeve; and a lock bushing fitting snugly but slidably on said punch and threaded into said opening, the inner end of said bushing seating against the projecting head portion of said punch to hold the latter solidly in the sleeve, said bushing having a wrench-engaging portion projecting from the sleeve and an accurately ground, cylindrical surface behind said wrench-receiving portion snugly fitting and guided by the ground, cylindrical surface of said opening to co-operate with said first-mentioned ground surfaces in holding the bushing and said punch centered precisely in the sleeve.

4. A punch-retaining assembly for punch presses of the type having a punch-carrying plate comprising a retainer sleeve adapted to be carried by said punch-carrying plate formed with a downwardly directed opening extending completely therethrough, the portion of the opening near the top end of the sleeve forming a socket, said opening having an internally threaded portion below said socket and an accurately ground, cylindrical portion below said internal threaded portion, and said socket having an accurately ground, cylindrical surface; a punch in said retainer sleeve having a head portion in and projecting from said socket and provided with the ground, cylindrical, peripheral surface snugly fitting and guided by the ground, cylindrical surface of the socket to hold the punch centered precisely in said sleeve; means for positively holding said punch angularly positioned in and against rotation relative to said retainer sleeve; and a lock bushing fitting snugly but slidably on said punch and threaded into said opening, the inner end of said bushing seating against the projecting head portion of said punch to hold the latter solidly in the sleeve, said bushing having a wrench-engaging portion projecting from the sleeve and an accurately ground, cylindrical surface behind said wrench-receiving portion snugly fitting and guided by the ground, cylindrical surface of said opening to co-operate with said first-mentioned ground surfaces in holding the bushing and said punch centered precisely in the sleeve.

5. A punch-retaining assembly for punch presses of the type having a punch-carrying plate comprising a retainer sleeve securable on said punch-carrying plate; a punch having an outwardly directed annular shoulder carried by said retainer sleeve; a lock bushing on the punch threaded into said retainer sleeve and bearing at the inner end thereof against said annular

shoulder to hold the punch solidly in the sleeve; and accurately ground cooperating surfaces on the retainer sleeve and the punch holding the latter positioned precisely in the sleeve against 5 rotation while permitting longitudinal adjustment of the punch therewithin.

6. A punch-retaining assembly for punch presses of the type having a punch-carrying plate comprising a retainer sleeve securable against rotation on said punch-carrying plate; a punch having an outwardly directed annular shoulder carried by said retainer sleeve; a lock bushing on the punch threaded into said retainer sleeve and bearing at the inner end thereof against said annular shoulder to hold the punch solidly in the sleeve; and accurately ground, cooperating surfaces on the sleeve and the body of the punch and on the sleeve and the bushing which holds said punch centered precisely in the sleeve and bushing in different positions of longitudinal adjustment of said bushing in said sleeve.

7. A punch-retaining assembly for punch presses of the type having a punch-carrying plate comprising a retainer sleeve, interengaging means 25 adapted to secure said sleeve against rotation on said punch carrying plate; a punch having an outwardly directed annular shoulder carried by said retainer sleeve; a lock bushing on the punch threaded into said retainer sleeve and bearing at the inner end thereof against said annular shoulder to hold the punch solidly in the sleeve; accurately ground, cooperating surfaces on the retainer sleeve and the punch holding the latter positioned precisely in the sleeve along its axis 30 while permitting longitudinal adjustment of the punch by adjusting the bushing in said sleeve, and means for holding said punch fixed against rotation in the sleeve.

8. A punch retainer comprising a sleeve having 40 a polygonal aperture through the center thereof at one end, an internal thread medially of the ends and a ground cylindrical wall which extends to the opposite end of the sleeve; and a bushing having a hollow interior for receiving a punch and having an external thread at one end and a ground cylindrical surface at the other, the thread and surface of the bushing mating with the thread and surface of the interior aperture of the sleeve.

9. A punch retainer comprising a sleeve having a polygonal aperture through the center thereof at one end, an internal thread medially of the ends and a ground cylindrical wall which extends to the opposite end of the sleeve; and a bushing 55 having a hollow interior for receiving a punch and having an external thread at one end and a ground cylindrical surface at the other, the thread and surface of the bushing mating with the thread and surface of the interior aperture of the sleeve, the bushing at the end having the thread being provided with an internal shoulder for receiving and supporting the head of a punch.

10. A punch retainer comprising a sleeve having a polygonal aperture through the center thereof at one end, an internal thread medially of the ends and a ground cylindrical wall which extends to the opposite end of the sleeve; and a bushing having a hollow interior for receiving a punch and having an external thread at one end and a ground cylindrical surface at the other, the thread and surface of the bushing mating with the thread and surface of the interior aperture of the sleeve, the end of the aperture opposite to that having the polygonal aperture being enlarged to form a recess for a plug for extending

the end of the punch from the assembled sleeve and bushing.

11. A punch having a cylindrical body of predetermined diameter and having a projecting portion which constitutes the working end of the punch; and a head on the opposite end of the body portion of cylindrical form of larger diameter than the body portion, said head having four flat faces on the sides thereof conforming in dimension to the four flat faces in the bore of a supporting sleeve with which the cylindrical head having the four flat faces mate.

12. A punch having a cylindrical body of predetermined diameter and having a projecting portion which constitutes the working end of the punch; a head on the opposite end of the body portion of cylindrical form of larger diameter than the body portion and having four flat faces on the sides thereof conforming in dimension to the four flat faces in the bore of a supporting sleeve with which the flat faces mate; said head having a tapped hole on its outer end, a washer-like plug, and a screw for securing the plug on the end of the head.

13. A punch-retaining assembly comprising a sleeve having a bore a portion of which at one end is of a form for receiving an element; interengaging means between said sleeve and element adapted to positively prevent turning movement therebetween for accurately locating the element relative to the sleeve while permitting relative longitudinal movement therebetween; a thread in the bore wall adjacent to said portion of predetermined form and an enlarged cylindrical surface at the opposite end of the bore; and a bushing having an external thread on its upper end and a cylindrical surface on its lower end for engaging the thread and cylindrical surface of the sleeve, permitting a predetermined longitudinal adjustment therebetween while being retained in accurate axial alignment.

14. A punch-retaining assembly comprising a sleeve having a bore therethrough one end of which is of predetermined form for receiving the head of a punch, interengaging means between the head and sleeve adapted to positively prevent

relative rotating movement therebetween while permitting a degree of relative longitudinal adjustment therebetween; the internal bore medially of the ends having an internal thread, the opposite end having a cylindrical surface; and a bushing having an external thread on one end and a cylindrical surface on the other which mate with the thread and the cylindrical surface of the sleeve.

15. A punch-retaining assembly comprising a sleeve having a bore therethrough one end of which is of predetermined form for receiving the head of a punch for locating the punch, interengaging means between the head and sleeve for positively preventing relative rotating movement therebetween while permitting a degree of relative longitudinal adjustment therebetween; the internal bore medially of the ends having an internal thread, the opposite end having a cylindrical surface; a bushing having an external thread on one end and a cylindrical surface at the other which mate with the thread and the cylindrical surface of the sleeve, the thread and surfaces being of such length as to permit the adjustment of the bushing a predetermined amount from the sleeve without disengaging the thread or the mating surfaces; and a punch for said assembly having a cylindrical body portion which extends through a cylindrical bore through the bushing and having a punch portion on the one end and having a head on the other end of such form as to mate with the portion of the bore of the sleeve of predetermined form.

OTTO MUELLER.
